US00D824921S

(12) **United States Design Patent** (10) Patent No.: **US D824,921 S**
Gillette et al. (45) Date of Patent: ** Aug. 7, 2018

(54) **DISPLAY SCREEN OR PORTION THEREOF WITH GRAPHICAL USER INTERFACE**

(71) Applicant: **Johnson Controls Technology Company**, Holland, MI (US)

(72) Inventors: **Theresa N. Gillette**, Wichita, KS (US); **Jedidiah O. Bentz**, Wichita, KS (US); **John Uerkvitz**, Wichita, KS (US)

(73) Assignee: **Johnson Controls Technology Company**, Auburn Hills, MI (US)

(**) Term: **15 Years**

(21) Appl. No.: **29/548,668**

(22) Filed: **Dec. 15, 2015**

(51) LOC (11) Cl. **14-04**

(52) U.S. Cl.

USPC **D14/485**; D14/492

(57) **CLAIM**

We claim the ornamental design for a display screen or portion thereof with graphical user interface, as shown and described.

DESCRIPTION

The FIGURE is a front view of the claimed design of a display screen or portion thereof with graphical user interface.

The broken lines showing the display screen and the remainder of the graphical user interface form no part of the claimed design.
